UNITED STATES PATENT OFFICE.

HERMAN L. STRONGSON, OF BROOKLYN, NEW YORK.

DESIGN FOR A MULTIPLE LAMP SOCKET.

Application filed March 4, 1922. Serial No. 1,041. Term of patent 7 years.

To all whom it may concern:

Be it known that I, HERMAN L. STRONGSON, a citizen of the United States, residing at Brooklyn, in the county of Kings and State of New York, have invented a new, original, and ornamental Design for Multiple Lamp Sockets, of which the following is a specification, reference being had to the accompanying drawing, forming part thereof.

Figure 1 is a side elevation of a multiple socket embodying my design, and,

Figure 2 is an end elevation thereof.

I claim:

The ornamental design for a multiple lamp socket as shown.

HERMAN L. STRONGSON.
